WAX TREATMENT BATH FOR USE IN HEAT THERAPY

John Edward Runnquist, 39 Kirby Cliff, Lowestoft, England, and John Woodcraft, 13 Oak Way, Halesworth, England

Filed Apr. 15, 1971, Ser. No. 134,534

Claims priority, application Great Britain Oct. 16, 1970

Term of patent 14 years

Int. Cl. D24—04

U.S. Cl. D83—1 C

FIG. 1.

FIG. 2.

FIG. 3.

FIG. 4.

FIG. 5.

FIG. 1 is a perspective view of a wax treatment bath for use in heat therapy showing our new design;

FIG. 2 is a bottom plan view thereof;

FIG. 3 is a top plan view thereof;

FIG. 4 is an end elevation thereof; and

FIG. 5 is a side elevation thereof.

We claim:

The ornamental design for a wax treatment bath for use in heat therapy, substantially as shown.
